UNITED STATES PATENT OFFICE.

ELMER E. LOVERING, OF DRACUT, AND JOSEPH A. PELLETIER, OF LOWELL, MASSACHUSETTS.

AUTOMATIC STOP MECHANISM FOR LOOMS.

No. 878,813.

Specification of Letters Patent.

Patented Feb. 11, 1908.

Application filed November 23, 1906. Serial No. 344,716.

To all whom it may concern:

Be it known that we, ELMER E. LOVERING and JOSEPH A. PELLETIER, of Dracut and Lowell, respectively, in the county of Middlesex and State of Massachusetts, have invented certain new and useful Improvements in Automatic Stop Mechanisms for Looms, of which the following is a specification.

10 This invention has for its object to provide simple and effective means for preventing a break-out in the warp threads in a loom, in case the shuttle remains in the shuttle-box at either end of its throw from any cause, 15 such as breakage or derangement of the lug strap, picker strap or other part of the loom.

The invention is embodied in an operating member adjustably mounted on the lay of a loom, and adapted to be held in its operative 20 position only when a shuttle is present in the shuttle-box, the said operating member when in its operative position being caused to transmit motion from the lay to suitable means for stopping the loom, such, for example, as a belt shipper adapted to shift the 25 driving belt from a fast to a loose pulley.

The invention consists in the several improvements which we will now proceed to describe and claim.

30 Of the accompanying drawings, forming a part of this specification,—Figure 1 represents a sectional elevation of that portion of a loom which includes the lay and adjacent parts, the portion of the loom illustrated being 35 equipped with an embodiment of our invention, which is shown with the operating member held in its operative position by a shuttle in the shuttle-box. Fig. 2 represents a view similar to Fig. 1, showing the operating 40 member in its inoperative position, which it normally assumes when the shuttle is out of the shuttle-box. Fig. 3 represents a front elevation showing the portion of the loom which contains the embodiment of our in- 45 vention illustrated in Figs. 1 and 2. Fig. 4 represents a top view of the portion of the loom shown in Fig. 3. Fig. 5 represents a perspective view, showing the parts embodying our invention operatively assembled.

50 The same letters of reference indicate the same parts in all the figures.

In the drawings, 12 represents the lay of a loom, the same being of the usual or any suitable construction, and carrying suitable shuttle boxes 13, adapted to arrest the shuttle 55 at the ends of its throw, as usual, each shut-

tle box having a suitable yielding shuttle binder 15, adapted to engage and be displaced by the shuttle. Suitable picker sticks 16 are employed to throw the shuttle, 60 as usual.

In carrying out our invention, we mount upon the lay an operating member adapted to communicate motion from the lay to suitable stopping means, such as a belt shipper, 65 adapted to shift the driving belt from a fast to a loose pulley, the said operating member being normally held in an inoperative position, and caused to operate to transmit motion to the belt shipper only when the shuttle 70 is not thrown from the shuttle-box at the proper time, and remains therein when the lay is moved forward to beat up the weft thread. The said operating member in this embodiment of our invention includes a 75 binder finger 17, which is pivoted upon the binder rod 18' suitably supported by the lay, the said finger projecting above the lay, and having its upper end in such proximity to the shuttle binder 15 that when said binder is 80 displaced by a shuttle remaining in the shuttle-box, it will displace the arm 17 from its operative position. The arm 17 is provided with an extension 18, which projects under the lay. When there is no shuttle in the 85 shuttle-box, the shuttle binder 15 and finger 17 are in the position shown in Fig. 2, the extension 18 being depressed so that its path of movement when moved by the lay is below the lug 19 hereinafter described. The normal 90 position of the operating member, composed of the arm 17 and extension 18, is as shown in Fig. 2. When the shuttle binder 15 is displaced by a shuttle which has failed to leave the shuttle-box at the proper time, 95 the displacement of the binder causes a corresponding displacement of the arm 17 and an upward movement of the extension 18, the latter being thus raised to position to engage the lug 19, as shown in Fig. 1. The lug 19 is 100 affixed to a slide 20, which is movable in fixed guides on the frame of the loom, said guides being preferably brackets 21 and 22, adjustably secured to the loom frame, and provided with slots which receive and permit 105 the endwise movement of portions of the slide 20. The said slide is provided at one end with an offset portion, on which is formed an ear or lug 23. The said offset portion is the part of the slide which is engaged 110 with the bracket 22, the ear or lug 23 being supported in position to bear upon one edge

of a knock-off lever 24, which is pivoted at 25 to the breast-beam 26 forming a part of the frame of the loom.

The knock-off lever 24 is normally in position to bear on a shipper lever 37, when said lever is in the position it occupies while the driving belt is engaged with the pulley on the driving shaft of the loom, the shipper lever being held in this position by engagement 10 with a notch 38 (Fig. 4) in a fixed guard plate 39. When the knock-off lever is moved from its normal position as hereinafter described, it forces the shipper lever out from the notch 38, whereupon the shipper 15 lever is forced by spring or other pressure into position to shift the driving belt onto a loose pulley, thus stopping the loom. The end portion of the slide 20, which is movable in the bracket 21, has a notch 27 in its lower 20 edge. When the slide is moved to the position shown in Fig. 1, the notch engages the lower end of the slot in the bracket 21, and permits the slide 20 to drop sufficiently to allow a latch or locking member 29 to drop 25 into position to engage a corresponding locking member 30 affixed to the lay 12, as shown in Fig. 1, this engagement of the members 29 and 30 locking the lay at one end of its movement.

30 The operation of the parts thus far described is as follows: It will be understood that the shuttle is thrown from its position at rest in the shuttle-box before the lay reaches the extreme of its backward movement, and that when the shuttle has been properly thrown, the extension 18 of the operating member will be depressed, when the lay reaches the extreme of its beating-up movement, so that said extension will not 35 contact with the lug 19. It will also be seen by reference to Fig. 1 that if a shuttle remains overtime in the shuttle-box, the arm 17 and extension 18 will remain displaced until the conclusion of the backward movement of the lay, so that the extension 18 will 40 encounter the lug 19 when the lay approaches the extreme of its backward movement, and will, therefore, cause a movement of the slide 20 in the direction indicated by the 45 arrow marked thereon in Fig. 1. This movement of the slide will cause the lug 23 to move the knock-off lever 24 sufficiently to release the shipper lever and shift the driving belt from the usual fast pulley which 50 it engages when running the loom, to the usual loose pulley which is engaged by the belt when the loom is not running. It will also be seen that the described movement of the slide 20 will bring the notch 27 therein 55 into the bracket 21, so that the slide 20 will be permitted to drop a distance equal to the depth of the notch 27 when said notch enters the bracket 21. This dropping of the slide causes the detent member 29, which rests 60 upon the lug 19, to drop correspondingly.

This dropping of the detent member 29 takes place just as the lay reaches its back center, so that the member 29 engages the member 30 on the lay, thus locking the lay and preventing its return movement. When the 70 loom has been thus automatically stopped, movement of the shipper lever to position to start the loom is prevented by the means next described, until the stopping mechanism has been properly adjusted or set for 75 operation.

34 represents a locking member adapted to lock the shipper lever when it is in position to hold the driving belt on the loose pulley, this being hereinafter termed the 80 inoperative position of the lever. Said locking member is an arm pivoted at 35 to a bracket secured to the frame. Said arm is provided at its lower end with a stud 33 which engages a slot 32 in a lug 31 on the 85 slide 20. The movement of slide 20 to release the shipper lever from the retaining notch 38 causes the upper end of the arm 34 to move into the position shown in Figs. 1 and 4, the arm being thus located in the path 90 of the lever and temporarily locking the latter and preventing it from engaging the retaining notch 38 and therefore from returning the driving belt to the fast pulley.

We claim:—

1. In a loom, a lay, an operating member adjustably mounted on the lay, and adapted to be held in its operative position by the presence of a shuttle in the shuttle-box, said operating member being inoperative when 100 the shuttle-box is empty, and means actuated by said operating member for throwing off the driving power of the loom and automatically and positively locking the lay at the end of its backward movement.

2. In a loom, a lay, an operating member adjustably mounted on the lay, and adapted to be held in its operative position by the presence of a shuttle in the shuttle-box, said operating member being inoperative when 110 the shuttle-box is empty, and means actuated by said operating member for positively locking the lay at the end of its backward movement.

3. In a loom, a lay, an operating member 115 adjustably mounted on the lay, and adapted to be held in its operative position by the presence of a shuttle in the shuttle-box, said operating member being inoperative when the shuttle-box is empty, and means actuated by said operating member for simultaneously stopping the loom and positively locking the lay at the end of its backward movement.

4. In a loom, a lay, an operating member 125 comprising a binder finger pivoted to the lay, and adapted to be displaced from its normal position by the shuttle binder, and an extension of said finger projecting from the lay, a slide movable in fixed guides, and having a 130

lug which is arranged to be encountered by said extension at the end of the backward movement of the lay when the operating member is displaced from its normal position, and a knock-off lever directly engaged with said slide.

5. In a loom, a lay, an operating member comprising an arm pivoted to the lay, and adapted to be displaced from its normal position 10 by the shuttle binder, and an extension of said arm projecting from the lay, a slide movable in fixed guides, and having a lug which is arranged to be encountered by said extension when the operating member is displaced from its normal position; said slide having means for permitting its depression when the slide is moved by the operating member, a detent member or latch supported by the slide, and adapted to be depressed 15 therewith and a complementary detent member on the lay to be engaged by the first-mentioned detent member to lock the lay.

6. In a loom, a lay, a shipper lever which normally holds the driving belt in its inoperative position, means for confining the shipper lever out of its normal position, an operating member adjustably mounted on the lay and operative only when a shuttle is in the shuttle-box, and means for transmitting motion from the operating member 20 to the shipper lever to release the latter from its confined position.

7. In a loom, a lay, a shipper lever which normally holds the driving belt in its inoperative position, means for confining the shipper lever out of its normal position, an operating member adjustably mounted on the lay and operative only when a shuttle is in the shut- 25

tle-box, and a knock-off lever normally in position to engage the confined shipper lever 40 and adapted to be moved by said operating member to release the shipper lever from its confined position.

8. In a loom, a lay, a shipper lever which normally holds the driving belt in its inoperative position, means for confining the shipper lever out of its normal position, an operating member adjustably mounted on the lay and operative only when a shuttle is in the shuttle-box, means for transmitting 50 motion from the operating member to the shipper lever to release the latter from its confined position, and means actuated by the operating member for temporarily locking the shipper lever in its inoperative position. 55

9. In a loom, a lay, a shipper lever which normally holds the driving belt in its inoperative position, means for confining the shipper lever out of its normal position, an operating member adjustably mounted on 60 the lay and operative only when a shuttle is in the shuttle-box, means for transmitting motion from the operating member to the shipper lever to release the latter from its confined position, and a pivoted locking 65 member engaged with the operating member and adapted to be moved by the latter into the path of the shipper lever.

In testimony whereof we have affixed our signatures, in presence of two witnesses.
